UNITED STATES PATENT OFFICE.

WILLIAM J. BRADLEY, OF TROY, NEW YORK, ASSIGNOR TO MONARCH STEAM BLOWER COMPANY, OF TROY, NEW YORK, A CORPORATION.

SOOT-EJECTOR FOR STEAM-BOILERS.

1,222,177.

Specification of Letters Patent. Patented Apr. 10, 1917.

Application filed February 7, 1912. Serial No. 675,963.

To all whom it may concern:

Be it known that I, WILLIAM J. BRADLEY, a citizen of the United States, residing at Troy, county of Rensselaer, and State of New York, have invented certain new and useful Improvements in Soot-Ejectors for Steam-Boilers, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a view in side elevation of a water-tube boiler provided with my improved soot-ejector.

Fig. 2 is a similar view of the same on an enlarged scale and partly broken away, showing one of the niches in the boiler-setting, with a plurality of nozzles arranged in a vertical series in said niche, and means for rotatively moving said nozzles simultaneously.

Fig. 3 is a cross-section taken on the broken line 3—3 in Fig. 2, through one of the pendulous doors which guards a nozzle-opening in the boiler-setting.

Fig. 4 is a vertical section taken on the broken line 4—4 in Fig. 3.

Fig. 5 is a cross-section taken on the broken line 5—5 in Fig. 4.

Fig. 6 is a central longitudinal section of one of the nozzle-heads detached.

Fig. 7 is a view in elevation of the inner side of the boiler-setting opposite one of the niches therein, and showing a series of pendulous doors closing the nozzle-openings from said niche into the draft-space of the boiler.

Fig. 8 is a vertical section of the same taken on the broken line 8—8 in Fig. 7.

This invention relates more particularly to the type of water-tube boiler wherein the water-tubes are arranged obliquely, and the principal object of the invention is to provide a boiler of such a type with soot-ejecting mechanism which can be easily and economically mounted in the boiler-setting.

A further object of the invention is to automatically protect the soot-ejecting nozzles from the excessive heat of the furnace when the nozzles are not in use.

Other objects will appear in connection with the following description.

In applying a soot-ejector to a water-tube boiler of this type, it has been found desirable to employ steam-ejecting nozzles rotatively mounted at one side of the boiler-setting opposite the intervals between successive horizontal rows of water-tubes, and rotatively movable in planes parallel with said water-tubes whereby jets of steam or air can be directed across and along the spaces between water-tubes; and this has heretofore been accomplished by mounting a plurality of nozzles upon a supply-pipe rotatively supported in an inclined position at right angles to the direction of the water-tubes at one side of the boiler-setting.

Such a soot-ejector, if mounted within the boiler-setting, requires a recess in the setting having walls inclined similarly to said pipe, and it is found in practice that the building of a boiler-setting with such inclined recessed walls is complicated and expensive, and requires the services of a highly skilled mason or brick-layer.

In carrying out my invention, I separately rotatively mount upon inclined axes a plurality of nozzles arranged in a vertical series in connection with a vertical supply-pipe within a vertical niche in the boiler-setting, in a manner calling for no unusual or expert skill on the part of the mechanic installing the device.

Referring to the drawings wherein the invention is shown in preferred form, 1, represents the body of the boiler; 2, the front water-leg; 3, the rear water-leg; and, 4, the water-tubes which extend in inclined position from front to rear of the boiler in connection with said water-legs.

The vertical baffles, 5, divide the spaces through which the water-tubes extend into three passes in the usual manner.

A soot-ejector is preferably mounted at the side of the boiler opposite each of said passes, and in Fig. 1, I have shown the boiler provided opposite each pass with a soot-ejector embodying my invention.

The boiler-setting, 6, is formed with a vertical niche, 7, in its outer side, and with a series of nozzle-openings, 8, extending from said niche through the inner side of the boiler-setting, said openings being opposite the respective intervals between the horizontal rows of water-tubes.

The openings, 8, arranged one directly above another, are preferably elongated longitudinally of the boiler-setting, and on inclined lines corresponding with the lines of inclination of the water-tubes.

Fixedly mounted within the niche, 7, is a vertical supply-pipe, 9, connected with a suitable supply of fluid under pressure, as with the steam-space of the boiler through the pipes, 10, controlled by suitable valves 11.

At points corresponding with the location of the respective nozzle-openings, 8, there are fixed upon the supply-pipe, 9, offsets 12, each forming a bearing for a nozzle, 13, as well as a means for connecting said nozzle with said supply-pipe.

The offset, 12, terminates in a bearing-box, 14, within which an inner offset end, 15, of the nozzle is rotatively mounted upon an axis at right angles to the direction of the inclination of the water-tubes.

The inner nozzle-member, 15, bears upon the packing-ring, 16, against which it is held by means of a coil-spring, 17, within the bearing-box.

The offset bearing-end of each nozzle has fixed thereon a beveled gear, 18, in engagement with a beveled gear, 19, fixed upon a vertical shaft, 20, which is rotatively mounted in bearings, 21, upon the bearing-boxes 14.

The shaft, 20, is shown angular in cross-section, and the gears, 19, are formed with cylindrical hubs, 22, which occupy cylindrical bearing-openings in the bearings 21.

The shaft, 20, can be rotatively moved by means of a crank, 23, or in any known manner, and when so moved will cause the several nozzles in the vertical series to be simultaneously moved through arcs in planes parallel with the direction of the water-tubes.

As the nozzles are thus rotatively moved, they are severally caused to traverse an arc represented by the dotted line, 24, the swinging end of a nozzle moving along said arc out of the niche, 7, through an opening, 8, to direct its steam-jet across and along the space between the water-tubes, and afterward being swung back through said opening, 8, into the niche, 7, where it is protected from the excessive heat of the furnace.

All the nozzles in a vertical series within a niche, 7, are thus simultaneously operated.

By rotatively mounting the nozzles upon inclined axes in connection with a vertical supply-pipe and a vertical operating-shaft, I am able to confine the ejecting-apparatus within a comparatively narrow space, making it possible to locate it all within a verti-

cal niche in the boiler-setting, thus greatly simplifying the installation of the apparatus.

By rotatively mounting the nozzles and the operating-shaft, 20, upon offsets from the vertical pipe, 9, the apparatus can be installed or removed as a unit, which greatly facilitates its installation.

As a means for protecting and shielding the ejecting-mechanism from the excessive heat of the furnace, I have shown each of the openings, 8, closed by a pendulous door, 25, rotatively supported by trunnions, 26, in bearings in a suitable frame or housing, 27, mounted in the boiler-setting, said doors 25 being severally adapted to swing upon an axis inclined to correspond with the inclination of the water-tubes.

The doors, 25, are adapted to be pushed open upwardly by the swinging ends of the respective nozzles, 13, as the nozzles are swung out through the respective openings, 8, and said doors, 25, are adapted to automatically close by their own weight when the nozzles are withdrawn into the niche 7.

The nozzles, 13, may be of any known form, a preferred form being shown in Figs. 4 and 6, wherein the head of the nozzle is shown provided with a divided outlet 28.

What I claim as new and desire to secure by Letters Patent is:

1. In a soot-ejector, and in combination, a vertical supply-pipe having an offset; a nozzle having an offset rotatively mounted upon said offset on the supply-pipe, said nozzle having an inclined axis of rotation; and means for rotatively moving said nozzle.
2. In a soot-ejector, and in combination, a vertical supply-pipe having an offset; a nozzle having an offset rotatively mounted upon said offset on the supply-pipe; and nozzle-rotating mechanism also mounted upon said offset on the supply-pipe.

3. In a soot-ejector, and in combination, a vertical supply-pipe; a plurality of nozzles rotatively mounted in connection with said supply-pipe, said nozzles having inclined axes of rotation; and means whereby said nozzles are rotatively moved upon their respective inclined axes.

4. In a soot-ejector, and in combination, a vertical supply-pipe; a plurality of offsets therefrom; a plurality of nozzles having offsets rotatively mounted upon the respective offsets on the supply-pipe, said nozzles having inclined axes of rotation; and means mounted upon the respective offsets on the supply-pipe for rotating the respective nozzles.

5. In a soot-ejector, and in combination, a vertical supply-pipe; a plurality of offsets therefrom; a plurality of nozzles having offsets rotatively mounted upon the respective offsets on the supply-pipe, said nozzles hav-

ing inclined axes of rotation; a vertical shaft mounted in bearings upon offsets on the supply-pipe; and intermeshing beveled gears on said shaft and on the respective nozzle-offsets.

6. In a soot-ejector, and in combination, a supply-pipe; a plurality of nozzles rotatively mounted in connection with said supply pipe, said nozzles having inclined axes of rotation; a shaft extending parallel with said supply pipe; and connections between said shaft and the several nozzles whereby they are rotatively moved upon the respective inclined axes.

15. 7. In a soot-ejector, and in combination, a boiler-setting provided with an inclined opening communicating with the draft-space of the boiler; a pendulous door rotatively supported upon an inclined axis and adapted to automatically close said opening; a nozzle rotatively movable through said opening upon an inclined axis, said nozzle being adapted to engage and automatically open said door; a supply-pipe communicating 25 with said nozzle; and means for swinging said nozzle to and fro through said opening.

8. In a soot-ejector, and in combination, a boiler-setting provided with a plurality of inclined openings communicating with the draft-space of the boiler; a vertical supply-pipe; a plurality of nozzles rotatively mounted in connection with said supply-pipe opposite the respective openings in the boiler-setting, said nozzles having inclined axes of rotation; means for rotatively moving said nozzles through the respective openings in the boiler-setting; and automatically closing doors for the respective openings in the boiler-setting, said doors being severally 40 pendulous on an inclined axis, and adapted to be engaged and automatically opened by the respective nozzles.

9. In a soot-ejector, and in combination, a boiler-setting provided with an outwardly opening vertical niche in its side-wall, and provided with a plurality of inclined openings extending from said niche to the draft-space of the boiler; a vertical supply-pipe located within said niche; a plurality of offsets from said supply-pipe; a plurality of nozzles having offsets rotatively mounted within said niche upon inclined axes upon the respective offsets on the supply-pipe opposite the respective openings in the boiler-setting; and means for swinging the nozzles through the respective openings.

10. In a soot-ejector, and in combination, a boiler-setting provided with an outwardly opening vertical niche in its side-wall, and provided with a plurality of inclined openings extending from said niche to the draft-space of the boiler; a vertical supply-pipe located within said niche; a plurality of offsets from said supply-pipe; a plurality of nozzles having offsets rotatively mounted

within said niche upon inclined axes upon the respective offsets on the supply-pipe opposite the respective openings in the boiler-setting; a vertical shaft rotatively mounted within said niche; and operating-connections 75 between said vertical shaft and the respective nozzle-offsets.

11. In a soot-ejector, and in combination, a boiler-setting provided with an outwardly opening vertical niche in its side-wall, and 75 provided with a plurality of inclined openings extending from said niche to the draft-space of the boiler; a vertical supply-pipe located within said niche; a plurality of offsets from said supply-pipe; a plurality of 80 nozzles having offsets rotatively mounted within said niche upon inclined axes upon the respective offsets on the supply-pipe opposite the respective openings in the boiler-setting; a vertical shaft rotatively mounted 85 upon the supply-pipe within said niche; and beveled-gear connections between said shaft and the respective nozzle-offsets.

12. In a soot-ejector, and in combination, a boiler-setting provided with an outwardly 90 opening vertical niche in its side-wall, and with a vertical series of inclined openings extending from said niche through the boiler-setting to the draft-space of the boiler; a pendulous door rotatively mounted 95 upon an inclined axis for closing each of said openings; a vertical supply-pipe located within said niche; a plurality of offsets from the supply-pipe; a plurality of 100 nozzles having offsets rotatively mounted within said niche upon inclined axes upon the respective offsets on the supply-pipe opposite the respective openings in the boiler-setting, said nozzles having members engageable with the respective doors to automatically open the same; and means for 105 swinging said nozzles through the respective openings.

13. In a soot-blower for water-tube boilers having inclined tubes, a fixed riser 110 mounted opposite the sides of the tubes, a set of pivoted nozzles communicating with the riser, arranged one above the other in vertical series and oscillating about non-coincident axes in the general direction of 115 the tubes, thereby following the dip of the tubes during the blowing operation.

14. In a soot-blower for water-tube boilers having inclined tubes, a fixed vertical riser mounted opposite the sides of the 120 tubes, a set of pivoted nozzles communicating with the riser, arranged one above the other in vertical series and oscillating about non-coincident axes in the general direction of 125 the tubes, thereby following the dip of the tubes during the blowing operation.

15. In a soot-blower for water-tube boilers having inclined tubes, a fixed vertical riser mounted opposite the sides of the tubes, a series of branches leading from the riser, 130

4
hollow joints on said branches arranged one above the other in vertical series, and nozzles leading from the joints and oscillating about the axes of the several joints, said axes being non-coincident and substantially at right angles to the dip of the water-tubes, whereby the nozzles follow the dip of the tubes during the blowing operation.

16. In a soot-blower for water-tube boilers having inclined tubes, a riser mounted opposite the sides of the tubes, a set of pivoted nozzles communicating with the riser, arranged one above the other in vertical series and oscillating about non-coincident axes in the general direction of the tubes, thereby following the dip of the tubes during the blowing operation.

17. In a soot-blower for water-tube boilers having inclined tubes, a vertical riser mounted opposite the sides of the tubes, a set of pivoted nozzles communicating with the riser, arranged one above the other in vertical series and oscillating about non-coincident axes in the general direction of the tubes, thereby following the dip of the tubes during the blowing operation.

18. In a soot-blower for water-tube boilers having inclined tubes, a vertical riser mounted opposite the sides of the tubes, a series of branches leading from the riser, hollow joints on said branches arranged one above the other in vertical series, and nozzles leading from the joints and oscillating about the axes of the several joints, said axes being non-coincident and substantially at right angles to the dip of the water-tubes, whereby the nozzles follow the dip of the tubes during the blowing operation.

19. In a soot-blower for water-tube boilers having inclined tubes, a riser mounted

opposite the sides of the tubes, a set of pivoted nozzles communicating with the riser, arranged one above the other in vertical series and oscillating about non-coincident axes in the general direction of the tubes, 45 thereby following the dip of the tubes during the blowing operation, and means whereby said riser remains stationary during the blowing operation.

20. In a soot-blower for water-tube boilers having inclined tubes, a vertical riser mounted opposite the sides of the tubes, a set of pivoted nozzles communicating with the riser, arranged one above the other in vertical series and oscillating about non-coincident axes in the general direction of the tubes, thereby following the dip of the tubes during the blowing operation, and means whereby said riser remains stationary 55 during the blowing operation.

21. In a soot-blower for water-tube boilers having inclined tubes, a vertical riser mounted opposite the sides of the tubes, a series of branches leading from the riser, hollow joints on said branches arranged one 65 above the other in vertical series, nozzles leading from the joints and oscillating about the axes of the several joints, said axes being non-coincident and substantially at right angles to the dip of the water-tubes, whereby 70 the nozzles follow the dip of the tubes during the blowing operation, and means whereby said riser remains stationary during the blowing operation.

In testimony whereof, I have hereunto set 75 my hand this 5th day of February, 1912.

WILLIAM J. BRADLEY.
